BATTING TRAINER

Norman J. Van Skyhawk, Salt Lake City, Utah, assignor
to Harman Killebrew Enterprises, Inc., Salt Lake City,
Utah

Filed June 9, 1969, Ser. No. 17,604

Term of patent 14 years

Int. Cl. D21—03

U.S. Cl. D34—5

FIG. 1

FIG. 2

FIG. 3

FIG. 4

FIG. 5

FIG. 6

FIGURE 1 is a perspective view of a batting trainer embodying my new design;

FIGURE 2 is a side elevation view of the batting trainer of FIGURE 1;

FIGURE 3 is a rear elevation view of the batting trainer of FIGURE 1;

FIGURE 4 is a front elevation view of the batting trainer of FIGURE 1;

FIGURE 5 is a top plan view of the batting trainer of FIGURE 1; and

FIGURE 6 is a fragmentary bottom plan view of the batting trainer of FIGURE 1.

I claim:

The ornamental design for a batting trainer, substantially as shown.
